[57] CLAIM

The ornamental design for an end surface of a set of slats for a glider seat, as shown and described.

DESCRIPTION

FIG. 1 is a perspective view of an end surface of a set of slats for a glider seat, showing my new design, the broken lines are for environmental purposes only and form no part of the claimed design.

FIG. 2 is a side elevational view thereof; and, FIG. 3 is a side elevational view thereof, similar to FIG. 2 but enlarged.
